HENRY HERMANI, OF BALTIMORE, MARYLAND, ASSIGNOR TO THE TIN DECORATING COMPANY OF BALTIMORE, OF BALTIMORE, MARYLAND, A CORPORATION OF NEW JERSEY

CAN TURNING MECHANISM

Application filed April 4, 1928. Serial No. 267,384.

This invention is an improvement in can turning mechanism, and more particularly in a mechanism for receiving axially moving formed can bodies and delivering them with **6** axes parallel.

Can bodies of the character in question are formed from suitable stock on mandrels, and are delivered in substantially axial alinement. That is, they move axially from the forming **10** machine.

For subsequent operation on the bodies, it is preferable that the bodies be received with their axes parallel, that is, that they be delivered to the machines for subsequent operations moving at right angle to their axes, or substantially so.

One of the primary objects of the present invention is the provision of a mechanism for receiving the axially moving bodies for **20** alining them, and for imparting to each body movement in a direction to swing the axis of the body at right angle to the direction of travel, and to deliver it in this position.

Another object is the provision of means **25** in connection with said mechanism for firmly but yieldingly grasping the bodies during the early part of their travel, and during the turning movement.

With these and other objects in view the **30** invention consists in the construction and novel combination of parts fully described hereinafter, illustrated in the accompanying drawings, and pointed out in the claims appended hereto, it being understood that various changes in the form, proportion, size **35** and minor details of construction within the scope of the claims, may be resorted to without departing from the spirit of the invention.

40 In the drawings forming a part hereof:—

Fig. 1 is a side view of the improved mechanism.

Fig. 2 is a plan view with parts broken away.

45 Figs. 3 and 4 are sections on the lines 3—3 and 4—4 respectively, of Fig. 1.

In the present embodiment of the invention, the mechanism is designed to receive can bodies 1 traveling from the mandrel of **50** a forming machine not shown, the bodies

being delivered from the forming machine moving axially. Each body in the present instance is provided near the end, which in the complete can will be the top, with an annular rib 2, and the bodies are delivered **55** with the ribbed end foremost.

The mechanism includes a suitable frame 3, in which is journaled a shaft 4, carrying a relatively large pulley 5, and a relatively large gear wheel 6, both the pulley and the wheel **60** being secured to the shaft. The shaft 4 is at the end of the frame remote from the forming machine, that is, at the delivery end of the mechanism; and near the opposite end, pulleys 7 and 8 are journaled on shafts **65** 9 and 10 respectively, held in the frame, and the shaft 10 is directly above the shaft 9.

A belt 11 is supported by the pulleys 5 and 7, and the relative arrangement of the shafts **70** 4 and 9, and the relative size of the pulleys 5 and 7 are such that the upper run of the belt 11 is horizontal. The lower run of the belt is engaged by a tension wheel 12, which is mounted for movement toward and from the run, the shaft 13 of the wheel being supported in a slot 14 in the frame, and adjustable in the slot.

Adjacent the shaft 4 a shaft 15 is journaled in the frame, the said shaft being a drive shaft and provided with a pulley 16, which **80** may be connected by a belt 18, with a suitable source of power, as for instance, the machine which performs the subsequent operations on the can bodies. The shaft also carries a spur gear 19, which meshes with gear wheel 6 **85** aforementioned to drive the shaft 4, and a pulley 20, which, with the pulley 8 supports a second belt 21.

Another pulley 22 is secured to the shaft **90** 4, and the lower run of belt 21 passes over said pulley. As shown in Fig. 3, the pulleys 5 and 22, and the gear wheel 6 constitute an integral structure having a hub 23 journaled on the shaft 4. The upper run of the belt 21 is engaged by a tension wheel 24, on a shaft **95** 25 connected to the frame in substantially the same manner as the shaft 13 aforementioned.

The pulleys 22, 20 and 8 are so arranged **100** that the lower run of the belt 21 travels paral-

61 el with the upper run of belt 11 in spaced relation, the spacing corresponding substantially to the diameter of the can body 1, so that when the bodies are between the co-
62 operating runs of the belts they are grasped with sufficient firmness to cause them to move with the belts, while at the same time they may be shifted in the manner to be presently described.

10 Referring to Fig. 3, it will be noticed that the pulley 22 is offset inwardly from the pulley 5, and that the belt 21 is much wider than the belt 11. The arrangement is such that that portion of the belt 21 which en-
15 gages the can at the pulley 5 is free from the pulley 22, extending above the upper run of the belt 11 in spaced relation.

Between the pulleys 5 and 7, and between the pulleys 8 and 5, the adjacent runs of the 20 belts 11 and 21 have guides 26 and 27 respectively, the guide 26 being below the upper run of the belt 11, while the guide 27 is above the lower run of the belt 21. These guides are plates which are supported from the frame by 25 arms 28 and 29 respectively, and the ends of the plates 26 and 27 are outturned as shown in Fig. 1.

As the can bodies pass from the forming machine between the cooperating runs of the 30 belts 11 and 21, they move in contact with an alining member 30. This member is arranged at the near side of the belts as shown in Fig. 1, and is supported by a bracket 31, mounted to slide in a guide 32 on the frame. 35 The member 30 is limited in its movement toward the frame, but may yield away from the frame. A coil spring 33 is arranged between the frame and the bracket and acts normally to draw the alining member toward the frame, the said member being limited in such movement, however, to the position of 40 Fig. 4.

As the can bodies leave the forming machine and enter between the cooperating runs of the belts 11 and 21, they move in contact with the alining member 30 which alines the can bodies axially. Just beyond the alining member a plate 34 is supported, by arms 45 extending laterally from the frame, and the end of the plate is in position to engage the forward ends of the can bodies at the side remote from the alining member 30, as shown in Fig. 2. Since the can bodies are traveling with the belts, the engaging of the side of the forward end with the plate will impart to the can bodies a quarter turn as also shown in this figure, and the bodies will swing around with the forward end abutting the plate 34 and will afterwards travel in this manner to the delivery end of the mechanism.

It will be apparent from the description and the drawings, that the can bodies are grasped and transported by flexible means, that is, the belts, and that at the points where the bodies are turned, the flexible means is

backed by the rigid guides. The arrangement of the upper belt with respect to the lower, provides for a secure grip on the bodies, as they pass around the wheel 5, and without liability to damage of the bodies.

What is claimed as new is:—

1. Mechanism of the class described, including belts having opposed runs to grasp and move a succession of axially alined can bodies, and means at one side of said belts for successively engaging the forward ends of the can bodies to shift said bodies a quarter turn, said last named means comprising a plate arranged with its plane substantially parallel with the direction of movement of the belts, and having one end positioned to engage the forward ends of the cans at one side of the belts.

2. Mechanism for receiving axially moving formed can bodies and delivering them with axes parallel, including belt conveyors having spaced parallel runs cooperating to grasp the formed can bodies, an alining device at one side of the belt, and a check at the other side for engaging the front ends of the bodies after they leave the alining device to impart to the bodies a quarter turn, said check including a plate positioned to engage at one end the body and along which the said end moves.

3. Mechanism of the class described, including belts having opposed runs to grasp and move a succession of axially alined can bodies, means at one side of the belts for engagement by the forward ends of the bodies to shift said bodies a quarter turn, and back-
100 ing plates for the belt runs to limit the movement thereof away from each other.

4. In a machine of the class described, a pair of belts having opposed runs to grasp a tubular can body, pulleys for supporting the runs, the pulley supporting the upper run being offset laterally with respect to the pulley supporting the lower run and the belt of the upper run being of a width to extend above the belt of the lower run at the pulleys.

5. In a machine of the class described, a pair of belts having opposed substantially parallel runs to grasp a tubular can body, pulleys for supporting the runs, the belt of the upper run being of greater width than the belt of the lower run, and the pulleys supporting the runs at the delivery end of the machine being offset laterally, so that that portion of the upper run at the pulleys is free.

6. Mechanism of the class described including belts having oppositely disposed runs spaced to positively engage with opposite sides of axially alined cylindrical can bodies received therebetween, means for moving said belts to carry the can bodies held therebetween in horizontal position, a member disposed between said belts to engage a portion of an approaching surface of a can

- body to cause the body to turn axially between the belts to change the direction of the axis of the body, and means in advance of said member to engage a surface of the approaching can bodies to aline them for effective engagement with the member, said means for moving the belts being so arranged that the rounded sides of the can bodies will be gripped with sufficient pressure by the belts to prevent the bodies from rolling out from between the belts during turning and carrying of the can bodies between the belts. 75
- 10 7. Mechanism of the class described including belts having oppositely disposed runs spaced to positively engage opposite sides of axially alined can bodies received therebetween, means for moving said belts to carry the can bodies, a member disposed between said belts to engage a portion of an approaching surface of a can body to cause the body to turn between the belts to change the direction of the axis of the body, and means in advance of said member to engage a surface of the approaching can bodies to aline them for effective engagement with the member, said member having an elongated portion to engage a surface of the can body after it has been turned to maintain cans in substantially parallel alined relation for delivery from the mechanism. 25
- 15 8. Mechanism for receiving axially moving formed can bodies and for delivering them with axes parallel, comprising a pair of pulleys mounted at the intake end of the mechanism, a driven wheel, a pair of pulleys on said wheel, a driving wheel meshing with said driven wheel, a pulley carried by said driven wheel, a pair of belts mounted around said pulleys with oppositely disposed runs in substantially parallel relation from the intake end to the outlet end of the mechanism to grasp opposite sides of the axially alined can bodies at the intake end, and means between said runs for engagement with an approaching surface of the successive can bodies to cause the can bodies to make a quarter turn between the opposite runs whereby the cans will be delivered at the outlet end with axes parallel. 30
- 20 9. The structure of claim 8 wherein the pulley supporting the upper run is offset laterally with respect to the pulley supporting the lower run and the belt of the upper run is of a greater width than the belt of the lower run. 35
- 25 10. The mechanism of claim 2 in which the alining device consists of an elongated plate positioned so that its alining face will always be parallel to the direction of motion. 40
- 30 11. The mechanism of claim 2 in which means are provided to prevent the turning of the can bodies while engaged with the alining device and in which the check is positioned a sufficient distance beyond the alining device so that the can bodies will be to- 45
- 50 tally disengaged from the alining device before engagement with the check. 55
- 55 12. In a mechanism of the class described, parallel flexible conveying belts, means for feeding alined cylindrical can bodies to said belts so that the rounded sides of said bodies will be gripped by said belts, said parallel belts being so arranged as to be spaced apart less than the external diameters of the can bodies, and an obstruction projecting part-way between the belts to contact with and cause the bodies upon movement hereof by the belts to be turned while gripped by said belts. 60
- 60 13. In a mechanism of the class described a conveyor for can bodies, and an elongated fixed plate parallel to the motion of the conveyor and projecting within said conveyor so that the forward end thereof will obstruct movement of the bodies and cause them to turn while being conveyed, the side of said plate serving to aline said bodies upon movement by the conveyor beyond said forward end. 65
